UNITED STATES PATENT OFFICE

2,426,309

ASSEMBLY OF ENGINE-AND-COMPRESSOR UNITS

Andrew Kalitinsky, Eagleville, Conn., assignor to
United Aircraft Corporation, East Hartford,
Conn., a corporation of Delaware

Application July 23, 1943, Serial No. 495,920

4 Claims. (Cl. 230—56)

1

This invention relates to the assembly of a free-piston engine-and-compressor unit.

Where weight of the unit is of prime importance, the connecting structure by which the several parts of the unit are held together must be as light in weight as possible. An object of this invention is to provide a light weight structure for connecting the compressors together and to the engine.

A feature of this invention is an arrangement of the interconnecting means between the opposed compressors of a free-piston engine-and-compressor unit so that the attaching means for the individual compressors will be in line with the means that hold the opposed compressors together.

Another feature of the invention is the use of a plurality of turnbuckles for urging the opposed compressors endwise into predetermined position.

Other objects and advantages will be apparent from the specification and claims and from the accompanying drawings which illustrate an embodiment of the invention.

Fig. 1 is a sectional view through the unit.

Fig. 2 is a side elevation of the unit of Fig. 1.

Fig. 3 is a fragmentary sectional view through one of the turnbuckles.

Fig. 4 is an inverted sectional view substantially along line 4—4 of Fig. 2.

The unit shown includes an engine cylinder 10 having reciprocating pistons 12 and 14 to which compressor pistons 16 and 18 in cylinders 20 and 22 are integrally connected. Sleeves 24 and 26 attached to the compressor pistons complete the reciprocating piston assemblies. The sleeves in combination with stationary pistons 28 and 30 form air spring cylinders.

The piston assemblies are moved apart by the burning of fuel injected into engine cylinder 10 by one or more devices 32. Air compressed in the air spring cylinders on the power stroke returns the piston assemblies. The assemblies are maintained always at equal distances from the center of the engine cylinder by a linkage which may include racks 34 meshing with a pinion 36.

Intake manifold 38 conducts air to intake valves 40 through which air alternately enters opposite ends of the compressor cylinders. The compressed air leaves the cylinders through discharge valves 42, also at opposite ends of the compressor cylinders, and passes through scavenge manifold 44 through ports 46 and 48 which are uncovered by pistons 12 and 14 at the end of the cycle thereby permitting air to be blown

2

through the engine cylinder and exhaust ports 50 and 52 into exhaust manifold 54.

Each compressor cylinder has outer and inner heads 56 and 58 interconnected by the cylinder wall 60. The engine cylinder is mounted within a housing 62 with which the inner heads 58 engage. The engine cylinder 10 may be axially located within the housing 62, as described in the copending Ledwith application, Serial No. 486,622, dated May 11, 1943, now Patent No. 2,412,344, dated June 5, 1946.

The inner heads 58 of the opposed compressor cylinders 20 and 22 are interconnected by a series of bolts 64, Fig. 4, each constituting a turnbuckle. These bolts when turned move the opposed compressors towards each other to hold flanges 66 and 68 on the inner heads against shoulders 70 and 72 on housing 62.

Each bolt 64 is threaded at one end to engage in a threaded boss 74 in the inner head of compressor cylinder 22. The other end of bolt 64 is headed and fits in a recess in a boss in the inner head of compressor cylinder 20. A threaded ring 76 in the recess engages the underside of the head of the bolt and holds it in position, although allowing the bolt to be turned by a flat-sided section 78 between its ends. When the compressors are placed in position at the opposite ends of the engine cylinder, as shown, the several bolts when tightened hold the heads securely against the central housing 62 and hold the opposed compressors 20 and 22 in predetermined relation to each other.

Cylinder heads 56 and 58 for each compressor may be held in place on cylinder wall 60 by right and left threads 80 and 82 at opposite ends of wall 60 engaging cooperating threads on heads 56 and 58. The cylinder wall then constitutes a turnbuckle by which the cylinder heads are connected.

The axis of each turnbuckle or bolt 64 is in the cylinder defined by the pitch circles of threads 80 and 82 which hold the compressor heads together. Thus any axial forces are transmitted by direct tension without developing any bending moments on the parts of the unit.

It is to be understood that the invention is not limited to the specific embodiment herein illustrated and described, but may be used in other ways without departure from its spirit as defined by the following claims.

I claim:

1. In a compressor assembly, opposed compressor cylinders having inner and outer heads, a housing between said inner heads and holding

said inner heads in spaced relation, an engine cylinder supported by said housing and turnbuckles extending between said inner heads and adapted by turning for holding the inner heads tightly against the housing, each turnbuckle having a head at one end, turning in a recess in one of the inner heads, and threads at the opposite end engaging a threaded recess in the other inner head.

2. In a compressor assembly, an engine cylinder, a housing extending around and supporting said engine cylinder, opposed compressor cylinders at opposite ends of the engine cylinder and in axial alignment therewith, each of said compressor cylinders including opposed cylinder heads and an interconnecting cylinder wall, the inner cylinder heads of the compressor cylinders engaging with and held in spaced relation by said housing, and several bolts extending between said inner compressor heads and holding said compressor cylinders in position against the housing, each bolt having its head mounted in a recess in the inner cylinder head of one compressor cylinder and having threads at the opposite end engaging with the inner head of the other compressor cylinder.

3. In a compressor assembly, an engine cylinder, a housing extending around and supporting said engine cylinder, opposed compressor cylinders at opposite ends of the engine cylinder and in axial alignment therewith, each of said compressor cylinders including opposed cylinder heads and an interconnecting cylinder wall, the inner cylinder heads of the compressor cylinders engaging said housing, and several bolts extending between said inner compressor heads and holding said compressor cylinder in position against the housing, each bolt having its head mounted in a recess in the inner cylinder head of one compressor cylinder and having threads at the opposite end engaging with the inner head of the other compressor cylinder, said bolt also having means between its ends by which it may be turned.

4. In a compressor assembly, an engine cylinder, a housing extending around and supporting said engine cylinder, opposed compressor cylinders at opposite ends of the engine cylinder and in axial alignment therewith, each of said compressor cylinders including opposed cylinder heads and an interconnecting cylinder wall, the inner cylinder heads of the compressor cylinders engaging said housing, recesses in the inner compressor cylinder heads, and a number of turnbuckles, each with its ends secured in said recesses and extending between the inner heads of the opposed compressor cylinders for moving the compressor cylinders into position against the housing and for holding the compressor cylinders in place against the housing, said turnbuckles being located substantially at the same radius from the axis of the assembly as the compressor cylinder wall.

ANDREW KALITINSKY.
